United States Patent

Des. 238,203

Patented Dec. 23, 1975

238,203

MICROFILM READER

Ralph M. Vigna, Rochester, N.Y., assignor to Eastman
Kodak Company, Rochester, N.Y.

Filed Feb. 1, 1974, Ser. No. 438,823

Term of patent 14 years

Int. Cl. D16—03

U.S. Cl. D61—1 Q

FIG. 1

FIG. 2

FIG. 3

FIG.4

FIG. 5

FIG. 6

FIG. 1 is a front elevational view of a microfilm reader showing my new design;

FIG. 2 is a top plan view thereof;

FIG. 3 is a right side elevational view thereof;

FIG. 4 is a left side elevational view thereof;

FIG. 5 is a rear elevational view thereof; and

FIG. 6 is a bottom plan view thereof.

I claim:

The ornamental design for a microfilm reader, substantially as shown.
